United States Patent Office

Des. 183,446
Patented Sept. 2, 1958

183,446

FRONT PANEL FOR A ROOM AIR CONDITIONER OR SIMILAR ARTICLE

Richard N. Brookins, Long Beach, Calif., assignor to
Essick Manufacturing Company, Los Angeles, Calif., a
corporation of California

Application March 29, 1957, Serial No. 45,491

Term of patent 14 years

(Cl. D62—4)

Fig. 1 is a front elevational view of a front panel for a room air conditioner or similar article showing my new design.

Fig. 2 is a cross sectional view on the line 2—2 of Fig. 1.

I claim:

The ornamental design for a front panel for a room air conditioner or similar article.
